UNITED STATES PATENT OFFICE.

HARRY S. KELSEY, OF BROOKLINE, MASSACHUSETTS.

DESIGN FOR A SETTLE FOR LUNCH-ROOMS.

47,792.

Specification for Design.

Patented Sept. 7, 1915.

Application filed July 14, 1915. Serial No. 40,136. Term of patent 7 years.

To all whom it may concern:

Be it known that I, HARRY S. KELSEY, a citizen of the United States of America, residing at Brookline, in the county of Norfolk and State of Massachusetts, have invented a new, original, and ornamental Design for Settles for Lunch-Rooms, of which the following is a specification, reference being had to the accompanying drawing, forming part thereof.

The figure is a perspective view of a settle for lunch-rooms, showing my new design.

I claim:

The ornamental design for a settle for lunch-rooms, as shown.

HARRY S. KELSEY.
